UNITED STATES PATENT OFFICE.

WILLIAM LAMDIN BAILIE, JR., OF NORFOLK, VIRGINIA.

NURSING-GARMENT.

No. 816,840.

Specification of Letters Patent.

Patented April 3, 1906.

Application filed July 7, 1905. Serial No. 268,668.

To all whom it may concern:

Be it known that I, WILLIAM LAMDIN BAILIE, Jr., of Norfolk, county of Norfolk, and State of Virginia, have invented a new 5 and useful Improvement in Nursing - Garments, of which the following is a specification.

This invention relates to garments for nursing - women, which garments are provided with openings for exposing the breasts when the infant is to be suckled and are formed with means for covering or closing the openings when the infant is removed, the design being that there shall be as little exposure of the person as possible when the infant is applied to the breast.

My invention consists of improvements in garments of this character, which improvements are directed to the form and arrangement of the coverings or flaps for the openings, the means for securing them in closed position, and to other features of construction, which will be fully described in the specification and the novel parts pointed out 25 in the claims.

In the accompanying drawings, Figure 1 is a front view of my improved garment on the person of the wearer with one of the covering-flaps closed and the other flap open. Fig. 30 2 is a front elevation with the flaps closed. Fig. 3 is a similar view with the flaps opened. Fig. 4 is a horizontal section through the garment, showing the flaps in closed position. Fig. 5 is a similar view showing the flaps 35 opened.

In the annexed drawings I have illustrated my invention as embodied in a knit undershirt, but it is manifest that the invention is applicable as well to undergarments of other 40 formation which are usually worn next the body.

In carrying my invention into effect I form in the front of the garment at points over the breasts of the wearer vertical slits or openings A A', of a length which while permitting of a sufficient protrusion of the breasts to admit of the infant being properly suckled will prevent the person from being unduly exposed. To the outer edge of each slit is connected the straight-edge b of a semicircular covering-flap B, the edges of said flaps being extended downward, as at b b', a considerable distance below the lower ends of the slits and being fastened along their extended 55 edges to the front of the garment.

When in closed position, the flaps extend

over and cover the respective slits and inward toward each other and are adapted to be fastened together conveniently by means of ribbons or strings C C', attached to the 60 edges of the flaps, and adapted to be tied together, as shown in Fig. 2, or, if desired, one of the flaps may be provided with a buttonhole to receive a button on the other flap.

When the breasts are to be exposed, the 65 flaps are disconnected and thrown back to the position in Figs. 1 and 3.

The extension of the flaps below the lower ends of the slits is of great importance and advantage in that the extended portion of 70 the flap will effectually cover the lower portion of the slit, notwithstanding the fact that the slit may gape or be widely opened, so that an effectual protection against exposure is afforded. Furthermore, there will be 75 more material in the flaps than if they terminated at the lower ends of the slits, which increased material will enable the flaps to properly conform to the bust without discomfort to the wearer or danger of exposure. 80

It is manifest that changes in details as to the form of the flaps, their arrangement with reference to the slits, and the manner of securing them in closed position may be adopted without departing from the limits of my 85 invention, the essence of which resides in extending the flap beyond the end of the slit and in providing means for fastening the flaps together when in closed position.

Having thus described my invention, what 90 I claim, and desire to secure by Letters Patent, is—

1. A nursing - garment provided with breast-openings, in combination with covering-flaps for said openings, and means independent of the garment for fastening said flaps together when in closed position. 95

2. A nursing-garment provided in its bust portion with vertical slits, in combination with covering-flaps secured to the outer edges 100 of said slits and adapted to extend inward toward each other over the slits, and means independent of the garment for fastening said flaps together to retain them in closed position. 105

In testimony whereof I hereunto set my hand, this 14th day of June, 1905, in the presence of two attesting witnesses.

WILLIAM LAMDIN BAILIE, JR.
